(57) **CLAIM**

Jul. 29, 2002 (JP) 2002-020195

The ornamental design for an operation controller for electronic computers, as shown and described.

(51) LOC (7) Cl. **14-02**

DESCRIPTION

(52) U.S. Cl. **D14/356**

(58) **Field of Search** D14/356-363;
D13/162, 184, 199; 312/223.1-223.3; 360/99.01-99.12;
361/690-696; 369/34.01, 36.01

FIG. 1 is a top, front and right side perspective view of an operation controller for electronic computers showing our new design,

(56) **References Cited**

FIG. 2 is a front elevational view thereof,

U.S. PATENT DOCUMENTS

FIG. 3 is a rear elevational view thereof,
